UNITED STATES PATENT OFFICE.

EDMUND S. HUNT, OF WEYMOUTH, MASSACHUSETTS.

DEVICE FOR LIGHTING FIRE-WORKS.

SPECIFICATION forming part of Letters Patent No. 228,760, dated June 15, 1880.

Application filed April 24, 1880. (No model.)

To all whom it may concern:

Be it known that I, EDMUND S. HUNT, of Weymouth, in the county of Norfolk and State of Massachusetts, have invented an Improvement in Roman Candles and other Fire-Works, of which the following is a full, clear, concise, and exact description, reference being had to the accompanying drawings, in which—

Figure 1 is a longitudinal section of a Roman candle with my improvement. Fig. 2 is a detail view of my lighting-wafer enlarged, and Fig. 3 shows a different form of cover for the lighting-wafer.

A represents the case; B, the filling; C, the outside wrapper or covering, and D my lighting-wafer. This lighting-wafer consists of a piece of straw-board or other stout paper with a hole through it, and this hole is filled with a plug, d, of composition like that used in the making of what are called "safety-matches," which is a compound of chlorate of potash, red lead, and lamp-black, and which will be ignited by friction with a surface coated with amorphous phosphorus.

In Roman candles, which should be lighted at one end, one of my wafers is pasted upon the end of the case A, as shown in the drawings, and is covered by the outer wrapper, C. In other kinds of fire-works the lighting-wafer will be used at the place where the piece is to be lighted, or at one end of a fuse, as will be clear without further description.

The wafer may be attached in any way to the case, or be made a part of the case.

The cover for the wafer is best made in the

usual way in Roman candles, and, as shown in Fig. 2, for larger fire-works, I prefer to use a tape and a paper cap, as shown in Fig. 3.

The rubber is a narrow strip of wood or stiff paper, one side of which is coated with 40 amorphous phosphorus; it is made in all respects like the lighting-surface of the box for safety matches.

In using my improved Roman candles the upper part of the wrapper D, which forms the 45 cover for the lighting-wafer, is torn off to expose the wafer, and the rubber is then rubbed over the composition d.

I do not claim the firing compound nor the rubber; nor do I claim the application of this 50 compound and rubber as a means of lighting fire-works, as all this is old; but

What I do claim as my invention is—

1. The combination of the lighting-wafer D, with its plug d of firing compound, case A, 55 filling B, and cover C, arranged over the lighting-wafer, and adapted to be readily removed when the firing compound is to be ignited, all substantially as described.

2. The lighting-wafer consisting of disk D, 60 of stout paper, perforated, and having the perforation filled with the plug d of firing compound, adapted to be ignited by friction, all substantially as described.

EDMUND S. HUNT.
